CLAIM

The ornamental design for a wall-mounted dispenser for surgical scrub solutions, substantially as shown and described.

DESCRIPTION

FIG. 1 is a top, front and left side perspective view of a wall-mounted dispenser for surgical scrub solutions showing our new design, with the broken-line disclosure of the container and nozzle being for illustrative purposes only and forming no part of the claimed design;

FIG. 2 is a left side elevational view thereof;

FIG. 3 is a front elevational view thereof;

FIG. 4 is a rear elevational view thereof;

FIG. 5 is a top plan view thereof; and,

FIG. 6 is a bottom plan view thereof.
